UNITED STATES PATENT OFFICE

RICHARD G. TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

YIELDABLE THREAD HOLDER FOR WEFT-REPLENISHING LOOMS

Application filed December 21, 1927. Serial No. 241,670.

This invention relates to improvements in yieldable thread holders for weft replenishing mechanisms and it is the general object of the invention to provide a thread holder of this type which will yield more readily in one direction than in another for purposes to be set forth.

In my co-pending application Ser. No. 241,671 I have set forth a thread holder including in its construction a resilient element which is interposed between the threads extending from the reserve bobbins and a fixed part of the magazine, so that said holder may yield at the time of transfer to prevent breakage of threads. It is found when a bobbin is being moved by the transerrer mechanism into the shuttle that the thread extending from the bobbin to the thread holder is placed under a temporary and sudden strain which occasionally results in breakage of the filling. The device set forth in said application also assists in clearing the shuttle box of the trailing end left by the incoming bobbin by whipping said end away from the cloth and out of the shuttle box at the time the temple cutter severs the thread from the selvage. The present invention retains the advantages of the mechanism shown in the aforesaid application and in addition assists in the threading of the shuttle.

The transfer of the bobbin occurs when the lay is in its extreme forward position but the shuttle is not ordinarily threaded by the transferring operation. After transfer the lay moves backwardly approximately one-half of its sweep before the shuttle is picked out of its box and the new bobbin of course moves rearwardly with the lay under these conditions. With a thread holder which is held in fixed position the thread is tightened during the backward stroke of the lay and may break. If the construction shown in the aforesaid application were made weak enough to permit easy movement of the thread holder rearwardly it would not be stiff enough to support all the ends which extend from the reserve bobbins. It is accordingly an important object of my present invention to provide a resilient thread holder which will offer relatively high resistance to

yield in a direction toward the magazine at the time of transfer but which will yield more easily in a rearward direction so that the same may follow the thread of the incoming bobbin as the lay moves from its foremost position back to picking position.

It is a more particular object of my present invention to provide a thread holder including in its construction a flexible element formed of a rubber tube along one element of which is formed an integral rib, said tube being held frictionally to a holder so that the same may be adjusted angularly. This is desirable inasmuch as it enables the weaver to vary the resistance offered in the two directions in which it is necessary for the holder to yield at the time of bobbin transfer.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a front elevation of a multicolor weft replenishing mechanism having my invention applied thereto, parts of the lay being shown.

Fig. 2 is a horizontal section taken on line 2—2 of Fig. 1.

Fig. 3 is a detail transverse vertical section taken on line 3—3 of Fig. 1.

Fig. 4 is a diagonal section taken on line 4—4 of Fig. 1 showing my improved resilient device in section,

Fig. 5 is a vertical section on line 5—5 of Fig. 4, and

Fig. 6 is a top plan view taken in the direction of arrow 6, Fig. 1.

Referring to the drawings, it will be seen that I have shown a magazine, a shuttle and a lay more or less diagrammatically to indicate the relative position these parts sustain toward each other. The lay 10 is provided with a shuttle S actuated by picker stick 11 extending through the slot 12 in the lay. A binder 13 extends through a guide 14 forming part of the mouth of the box and said guide has a vertically extend-

ing wall 15 as shown in Fig. 3 and a horizontal upper shelf 16. A temple 17 may be of the usual form and is provided with a thread cutter 18 shown in Fig. 2.

5 The weft replenishing mechanism includes a magazine 19 having inside and outside plates 20 and 21, respectively, which guide the stack of bobbins 22. At the time of indication of weft exhaustion by weft detecting mechanism not shown the stack of bobbins will move downwardly an amount equal substantially to the diameter of one of the bobbins and when the shuttle which has indicated substantial exhaustion again arrives 10 under the magazine 19 the lowermost bobbin of the stack will be lowered to transfer position by mechanism not shown. Each bobbin has extending therefrom a thread 23 and said threads move downwardly with the bobbins. The matter thus far described is 15 common construction in automatic or weft replenishing multicolor looms and forms no part of my present invention, reference being had to patent to Ryon No. 1,030,748 for the weft replenishing features and to No. 25 630,236 to Joy for the temple cutter.

My present invention relates more particularly to the form of the yielding part of a thread holder and by referring to Figs. 1 and 5 it will be seen that I have provided a tubular device 40 made preferably of india rubber and having a bore 41 therethrough. A thread holder 43 formed of bent wire circular in cross-section is secured to the 30 outside frame 21 of the weft replenishing mechanism by means of bolt 44 and has a diagonally extending shank 45 lying in a vertical plane substantially parallel to the axis of the shuttle. The shank 45 is slightly 35 larger than the bore 41 and is inserted into the latter, whereby the tubular portion 41 is held frictionally to the wire holder 43. A thread retainer 46 is inserted into the lower 40 end of the tube 41 and is frictionally held in proper angularly adjusted position. The manner of connecting the tubular device with the shank 45 and the retainer 46 is set forth clearly in Fig. 4.

As previously stated it is desirable that 50 the thread holder be free to move rearwardly under very slight pressure so that the same may follow the lay as the latter moves backwardly after a transferring beat of the loom. It is necessary, however, to keep the 55 resilient element sufficiently stiff to hold the trailing ends 23 above the path of the lay and also to give a sufficiently quick and decisive withdrawing movement to the end extending from the retainer 46 to the selvage 60 when the thread is severed by the temple cutter 18. To accomplish these results I form integrally with the tube 40 a rib 50 which as shown in Fig. 1 lies in a vertical plane so that it will add increased resistance 65 to the movement of the tube 40 from the full

to the dotted line position shown in Fig. 1 but will add practically nothing to the resistance offered by said tube when it is moved rearwardly from the full to the dotted line position shown in Fig. 6. By adjusting 70 the tube and the rib with respect to the shank 45 a variety of angular positions of said rib may be secured so that the tension desired by any particular user may be obtained.

In operation at the time of transfer the tube 40 with its rib may be deflected to the dotted line position shown in Fig. 1 to relieve any tension which might occur in the trailing end 23 extending from the freshly 80 transferred bobbin. Should the said end lie behind the wall 15 and at a relatively large distance below the shelf 16 the tube will yield sufficiently to prevent breakage. After transfer, as the lay moves rearwardly preparatory to picking, the eye of the shuttle will not be threaded and it may be difficult for the weft or filling to be unwound from the freshly inserted bobbin and under these conditions the flexible device will yield by 85 moving from the full to the dotted line position shown in Fig. 6. It is to be observed that this latter movement of the tube is not resisted by the rib 50 as it is desirable to offer as little resistance as possible to the 90 rearward movement of the thread retainer. The conditions under which the shuttle is threaded will be improved if the end of the thread extending from the freshly inserted bobbin and attached to the retainer 46 could move rearwardly at the same rate as does the lay so that said retainer and shuttle would always be in vertical alignment. The 95 easy yielding of the tube 40 permits this rearward movement of the retainer and thereby improves threading conditions.

From the foregoing it will be seen that I have provided an improved form of yieldable thread holder having a yielding element weak enough to move toward the magazine under 100 the action of a single thread but sufficiently strong to hold all of the threads above the lay, and that said yielding element can be bent by the exertion of a very small force to move the retainer 46 rearwardly with the lay to assist 105 in the threading of the shuttle.

Having thus described my invention it will be apparent that changes and modifications may be made therein by those skilled in the art without departing from the spirit and 110 scope of the invention and I do not wish to be limited to the details herein disclosed, but what I claim is:

1. In a thread holder for a weft replenishing loom having a supply of reserve bobbins 115 and an active shuttle, a thread retainer, a device formed of resilient material supported by the loom and affording support for the retainer, the ends of the filling extending from the reserve bobbin being attached to the 120

130

thread retainer, and a rib formed on said resilient device to increase the resistance thereof to deflection in one direction.

2. In a thread holder for a weft replenishing loom having a supply of reserve bobbins and an active shuttle, a thread retainer, a device formed of resilient material supported by the loom and affording support for the retainer, the ends of the filling extending from the reserve bobbin being attached to the thread retainer, and a rib formed on said resilient device to increase the resistance thereof to deflection in one direction, said rib lying in a substantially vertical plane to cause the resilient device to offer more resistance to deflection in the direction in which the shuttle is picked than is offered thereby to movement in a rearward direction.

3. In a thread holder for a weft replenishing loom having a supply of reserve bobbins and an active shuttle, a thread retainer, a device formed of resilient material supported by the loom and affording support for the retainer, the ends of the filling extending from the reserve bobbin being attached to the thread retainer, and a rib formed on said resilient device to increase the resistance thereof to deflection in one direction, said resilient device being angularly adjustable relatively to the loom, whereby the location of the rib may be changed.

4. In a thread holder for a weft replenishing loom having a supply of reserve bobbins, a lay, and an active shuttle, a resilient device supported by the loom and having operatively connected thereto the threads which extend from the reserve bobbins, said device having a cross section unsymmetrical about the axis thereof to render said device more resistant to bending strains in a vertical plane than in a horizontal direction parallel to the motion of the lay.

5. In a thread holder for a weft replenishing loom having a supply of reserve bobbins, a lay, and an active shuttle, a resilient device supporting the ends extending from the reserve bobbins, said device having a cross section unsymmetrical about the axis thereof to render said device more resistant to bending strains in a vertical plane than in a horizontal direction parallel to the motion of the lay.

6. In a thread holder for a weft replenishing loom having a supply of reserve bobbins, a lay, and an active shuttle, a resilient device affording support for the ends of filling extending from the reserve bobbins, said device having a cross sectional area unsymmetrical about the axis thereof to render said device more resistant to bending strains in a vertical plane than in a horizontal direction parallel to the motion of the lay, said device offering a relatively high resistance at the time of transfer of the reserve bobbin in the direction in which the shuttle is picked to prevent breakage of the thread, and offering a relatively

low resistance to movement rearwardly as the shuttle moves backwardly after a transfer.

7. In a thread holder for a weft replenishing loom having a supply of reserve bobbins, a lay, and an active shuttle, a resilient device affording support for the ends of filling extending from the reserve bobbins, said device having a cross sectional area unsymmetrical about the axis thereof to render said device more resistant to bending strains in a vertical plane than in a horizontal direction parallel to the motion of the lay, said device offering a relatively high resistance at the time of transfer of the reserve bobbin in the direction in which the shuttle is picked to prevent breakage of the thread, and offering a relatively low resistance to movement rearwardly as the shuttle moves backwardly after a transfer, said resilient device being angularly adjustable relatively to the loom.

In testimony whereof I have hereunto affixed my signature.
